UNITED STATES PATENT OFFICE.

WELLING FISKE THATCHER, OF NEW YORK, N. Y., ASSIGNOR TO SERVEL, INC., OF NEW YORK, N. Y., A CORPORATION OF DELAWARE.

MULTIPLE-INSTALLATION-REFRIGERATION SYSTEM.

Application filed May 23, 1928. Serial No. 279,946.

My invention relates to refrigeration systems of the type known as multiple installations which are intended primarily for apartment houses.

In multiple installations a plurality of evaporator units placed in different refrigerators, usually in different apartments, one above the other, are connected to a common compressing and condensing unit, usually located in the basement of the apartment house.

Such systems contain a considerable charge of refrigerant and as many refrigerants are harmful and others are irritating, if not actually harmful, it is advisable to guard against leakage because a leak in one apartment is liable to let a large amount of refrigerant corresponding to many refrigeration units into the one apartment.

Some present systems have thin pipes concealed in walls which have been known to be punctured by nails driven into the walls and are inaccessible in case of leakage. Others are arranged so as to be more or less hazardous.

All refrigerating systems at present used for multiple installations have a high pressure side and a low pressure side. The principal content of the high pressure side is liquid refrigerant and the principal content of the low pressure side is gaseous refrigerant. Of the two parts of the system thus defined, the high pressure side containing the liquid refrigerant deserves more attention from the point of view of safety due to the fact that a minute amount of liquid refrigerant is equivalent to a relatively high amount of gaseous refrigerant. In other words, assuming that the two sides of the system be isolated, a leak in the low pressure side is not at all serious compared to a leak in the high pressure side. A small amount of liquid refrigerant escaping through a leak causes a large amount of gaseous refrigerant when expanded into a room. My system takes these features into consideration in providing a system wherein the liquid or high pressure line is completely enclosed within the low pressure line so that I obtain a dual safety provision in that, first, the liquid line is protected by the outer low pressure line, which I make a rugged construction, wherefore a leak in the liquid line is unlikely, and, second, should a leak in the liquid line occur despite the pro-

tection thus afforded, the leakage will be into the low pressure line which is connected to the suction side of the compressor and such leakage will not be into a room.

An objectionable feature of many multiple type installations at present used is that a leak anywhere in the riser pipe system extending up through the building is communicated to all apartments in the same tier due to the interconnection of the apartments by means of what may be termed flues through which the riser connections extend. My novel system is so constructed and arranged that should a leak occur in one apartment the refrigerant passing through such a leak will not be communicated to any other apartment by any flues, tubes, or pipes or other type of conduit or passages associated with the refrigerating system.

I prefer to have the riser connections of my system arranged exposed within the rooms through which they pass and so colored as to indicate the refrigerant contained therein. This feature is principally for protection in case of fire.

Further objects and advantages of the invention will be apparent from the following description taken in connection with the accompanying drawing on which:

Fig. 1 shows diagrammatically a house in cross-section with refrigerators on different floors in different apartments, the arrangement embodying the present invention;

Fig. 2 is a sectional view, taken on line 2—2 of Fig. 3, of a junction box forming part of the system of Fig. 1;

Fig. 3 is a side view of the junction box of Fig. 2;

Fig. 4 is a sectional view taken on line 4—4 of Fig. 2;

Fig. 5 is a longitudinal sectional view of a modified junction box taken on line 5—5 of Fig. 6;

Fig. 6 is a full view of the junction box of Fig. 5;

Fig. 7 shows still another form of junction box; and

Fig. 8 shows a preferred pipe guard for the system of Fig. 1.

Referring more particularly to Fig. 1, which shows generally a multiple installation embodying my invention, reference character 10 designates the basement floor of an apartment house. The first, second and third floors of the apartment house are

designated by reference characters 11, 12 and 13 respectively. The roof is indicated at 14. 15 is a general reference character for refrigerators, letters following the number indicating the floor in respective alphabetical order. Likewise 16^a, 16^b, and 16^c designate junction boxes for the respective refrigerators. The junction box in the basement is indicated by the suffix "x". I prefer two types of junction box, one of which may be termed left hand and the other right hand. Except for being right and left hand, the junction boxes of Fig. 1 are alike and are shown in detail in Figs. 2, 3 and 4. Riser pipes extend vertically between the junction boxes, the high pressure liquid lines being inside the low pressure gas lines. The low pressure outer gas lines are shown at 17 in Fig. 1. Reference character 18 designates guards for the riser pipe which are preferred but which may be omitted. The compressor 19, motor 20 and condenser 21 are arranged in the basement and are suitably connected to each other and to junction box 16^x.

Referring now to Figs. 2, 3 and 4, the junction box designated generally at 16 comprises a main box casting or forging member 22 and a cover 23 therefore. The main box member has lugs 24 for attachment to the wall of the apartment. It is hollow and has a central ridge 25 which, when the junction box is in normal position, is at an angle of 45° to the horizontal. Ridge 25 has an internal bore 26, plugged at the end by a plug 28 and having three channel connections 30, 31 and 32.

A liquid line 33' extending up from below is connected to channel connection 30. A liquid line 33" for carrying liquid refrigerant on up to the next higher apartment is connected at channel connection 31. A valve 34 has one connection threaded into the main box member 22 so as to be connected to channel connection 32 and has another connection 35 for connection to the liquid refrigerant supply line designated generally by reference character 36 in Fig. 1, connected to the local refrigerator.

A second valve 37 is connected to a passage 38 leading to the space 40 of the main box member just under the cover and around the ridge 25 and outside pipes 33. This valve 37 is connected at 41 to the gas space of the evaporator within the local refrigerator cabinet. The gas or vapor connections are generally designated by reference character 42 in Fig. 1.

The gas conduits 17 are connected directly with space 40. The cover 23 is secured to part 22, so as to make a tight joint.

It will be obvious from the above that should there be a leak in the liquid line, the escaping fluid will merely pass into the low pressure suction line and will not get out

into the apartment. Also it will be seen that the heavier outside piping 17 and the junction boxes constitute a protection for the liquid line. At the places where conduits 17 pass through the floors I provide a tight connection (at 43) wherefore no refrigerant can leak from one apartment to another along any portion of the system. By removing cover 23, access is had for inspection of the liquid line connections and the arrangement is such that all connections are accessible with ease. By having the conduits 17 connected at diagonal parts of the junction box, assembly is facilitated. Also expansion and contraction is taken care of. The liquid line pipes are coiled somewhat within the junction boxes thus facilitating assembly. Each refrigerator can be connected or disconnected without affecting any other refrigerator.

I prefer that the guards 18 be made so as to present a large outward angle with respect to the wall (see Fig. 8). This prevents damage to the riser pipes due to moving of furniture and the like. The guards and pipes should be painted to indicate the gas contained therein. Amongst other advantages, this would warn a fireman that the pipe should not be severed.

I also provide a safety valve 44, conveniently located, connected to the space 40 of the upper junction box 16^c by a pipe 45 and connected to discharge above the roof by means of a pipe 46.

By appropriately fitting the junction boxes with holes, some of which would be plugged, it is evident that I may use one type of junction box for all junctions.

Should a leak occur from the liquid line into the outer low pressure piping, the pressure in the outer piping will obviously rise. I therefore provide a pressure responsive element 48 adapted to open the motor circuit in case the suction line pressure rises above a predetermined excessive value.

Referring now to Figs. 5 and 6, the junction box is again designated at 16, though of different form, and the liquid lines are numbered 33 and the outer gas lines 17. The liquid lines are connected to a passageway 26 in the junction box, the pipes 33 being spread at the ends as indicated at 49 and hollow studs 50 are forced against the spread portions to make tight joints preventing leakage between the liquid passageway and the gas passageway. A hole 51 serves for an outlet connection and a hole 52 for an inlet connection to the local evaporator unit. It is obvious that the advantages of this arrangement are, in general, the same as of the previously described embodiment.

Fig. 7 shows another form having the same characteristics. Like reference characters designate corresponding parts in the different figures. In Fig. 7 the ends of liquid

lines 33 are flared to make the necessary joints.

It will be understood that the invention permits of other forms than those disclosed.

5 Having thus described my invention, what I claim is:

1. A multiple installation refrigerating system comprising a compressor, a condenser, evaporators for different refrigerators, a junction box for each of a plurality of refrigerators, said junction box comprising separate liquid and gas channels, gas conveying conduits connecting gas channels of different junction boxes and liquid conveying 10 conduits connecting the liquid channels of different junction boxes, said liquid conveying conduits being located within said gas conveying conduits and the aforementioned parts being otherwise interconnected to form 15 a circulation system for refrigerant.

20 2. A multiple installation refrigerating

system comprising a vertical riser including low pressure refrigerant gas lines, high pressure liquid refrigerant lines within said gas lines, junction boxes interposed in said vertical riser, means within the junction boxes for connecting the liquid refrigerant lines while isolating the liquid lines from the gas lines and arranged for connecting the liquid lines to an evaporator and a connection for 25 connecting the evaporator with the gas lines.

3. A junction box for use in refrigerating systems comprising a casing having a first space for passage of gaseous fluid and a second space for passage of liquid fluid, means 30 for connecting a plurality of pipes to said second space so that said pipes pass within said first space and separate connections for connecting the spaces with an evaporator.

35 In testimony whereof I have affixed my signature.

WELLING FISKE THATCHER.
